APPARATUS FOR PRODUCING AND STOR-
ING OXYGEN

Adolf Messer, Frankfort-on-the-Main, Germany

Application October 17, 1936, Serial No. 106,165
In Germany September 4, 1936

2 Claims. (Cl. 62—122)

In certain types of air separating plants for the production of oxygen and nitrogen, the liquid oxygen produced and collected in the rectification column is forced out by a low pressure, for instance about 0.5 atm., into the oxygen evaporating coil on the low pressure side of the apparatus where the liquid oxygen is evaporated. The warmer or outlet end of the oxygen evaporating coil is generally connected to a gas holder of the floating bell type where the oxygen accumulates and from which it is withdrawn and compressed for storage at a high pressure.

In many cases, especially where the oxygen is produced at the plant where it is to be consumed, a pressure of only about 10 atm. is required, so that any compressing of the oxygen to any higher degree entails unnecessary expenses. An oxygen producing plant suitable for such oxygen users has been so well developed that even an intermittent operation of the plant is economical and the accumulation of very large quantities of oxygen in order to insure a constant supply is not necessary.

One object of the present invention is to provide a process and apparatus for separating oxygen from air and storing said oxygen at a suitable pressure for use without further compressing or the provision for very high pressure storage.

In carrying out the present invention, I provide one or more liquid oxygen receivers which are advantageously directly connected with the bottom of the rectification column to receive the liquid oxygen from said column. After the receiver has been filled to a predetermined level, the liquid oxygen supply thereto is shut off and the stored oxygen is forced through the oxygen evaporating coils forming part of the heat interchanger for precooling the incoming air. The very low temperature which exists in the filled receiver normally inhibits rapid evaporation of the liquid oxygen, and in carrying out the present invention, pressure is utilized for forcing out the liquid oxygen from said receiver. For instance, the second stage of the air compressor may be utilized as such pressure means.

Preferably more than one receiver is provided, and the receivers are filled and emptied alternately so that while one receiver is being filled with liquid oxygen, the liquid oxygen which has already been stored in the other receiver is forced by air pressure through the oxygen evaporating coils, as already pointed out.

At the outlet or warmer end of the oxygen evaporating coils, there is provided a storage gas

holder for receiving the evaporated oxygen. An adjustable regulating valve in the piping between the oxygen evaporator coil and the storage holder, regulates the amount of vaporization of the liquid oxygen and effects the storing of the gaseous oxygen in the holder at the desired pressure.

In the accompanying drawing there is shown for the purpose of illustration, an apparatus which embodies the present invention and which may be used to carry out my improved process.

In this drawing there is shown a column 10 having a heat interchanger 11 at the upper end for precooling the incoming air, and a rectifying section 12 at the lower end for separating the air into oxygen and nitrogen. The air is introduced under pressure through a coil 13 of the interchanger 11 in countercurrent heat interchange relationship with the coil 14 through which the evaporation of the separated liquid oxygen takes place. This precooled air, after leaving the heat interchanger 11, passes through a coil 15 at the bottom of the rectifying section where the separated liquid oxygen collects, and then through an expansion valve 16 to a nozzle disposed over a series of trays 18.

As the resulting liquid air trickles downwardly over the trays 18, the nitrogen gas passes upwardly around the heat interchanger 11 and out through an outlet 20 while the oxygen collects in liquid form at the bottom of the column.

As a feature of the present invention, the liquid oxygen collected at the bottom of the column 10 is gradually withdrawn and temporarily stored in a receiver before passing through the heat interchanger coil 14. As shown, a pipe 24 is connected to the bottom of the column 10 and has a pair of branch outlets 25 and 26 extending into the tops of two receivers 22 and 23, these branches being controlled by valves 27 and 28.

Extending substantially from the bottoms of the receivers 22 and 23 are outlet pipes 30 and 31 forming branches of a pipe 32 connected to the inlet end of the oxygen evaporating coil 14. These outlet pipes are provided with valves 33 and 34.

Means are provided for forcing the liquid from either of the receivers 22 and 23 through the evaporating coil 14 of the heat interchanger 11. For this purpose there is provided a pipe 36 leading from a suitable source of pressure such as the second stage of the air compressor, and having a pair of branch connections 37 and 38 which lead respectively into the upper ends of the receivers 22 and 23, and controlled by valves 40 and 41.

The outlet end of the oxygen evaporating coil 14 leads to a storage holder 42, the connection between said coil and said holder being controlled by an adjustable regulating valve 43. This holder 42 is provided with a valved outlet 44 leading to a suitable point where the oxygen may be used in the workshop.

As the oxygen is separated and collected in liquid form in the bottom of the column 10, it is 10 delivered to and from the receivers 22 and 23 alternately. As shown in the drawing, the valves 27, 34 and 41 are opened and the valves 28, 33 and 40 are closed, so that the liquid oxygen is being delivered through the valve 27 into the 15 upper end of the receiver 22 while the liquid oxygen which has already been stored in the receiver 23 is forced by the pressure in the pipe 36 through the valve 34 and into the evaporating coil 14. The evaporated oxygen leaving the 20 coil 14 passes into the storage holder 42 at a pressure depending on the adjustment of the valve 43. When the liquid reaches the desired level in the receiver as shown by the gauge glass 45 or by other suitable means, the valves are 25 reversed. By reversing the valves at the proper intervals, liquid oxygen may be continuously produced and continuously withdrawn from the col-

umn at low pressure, and liquid oxygen continuously evaporated and stored at a readily usable high pressure without the use of any additional pumping or compressing mechanism.

Having thus described my invention, what I 5 claim as new and desire to secure by Letters Patent is:—

1. An air separating apparatus including a rectification column, a heat interchanger, a liquid oxygen receiver connected to the liquid oxygen collecting portion of said column, a delivery pipe from said receiver to said heat interchanger, and means for forcing air under pressure into said receiver to force the liquid oxygen therein through the heat interchanger. 10

2. An air separating apparatus including a rectification column, a heat interchanger, a pair of liquid oxygen receivers, valved means between the bottom of said rectification column and said receivers for delivering liquid oxygen from said column selectively to either one of said receivers, valved means for delivering liquid oxygen from either one of said receivers through said heat interchanger, and air pressure means for forcing the liquid oxygen from either one of said receivers through said heat interchanger. 15 20 25
